DESIGN FOR A CABINET

Samuel J. Block, Connersville, Ind., assignor to
Steel Kitchens Corporation, Connersville, Ind.,
a corporation of Illinois

Application February 23, 1935, Serial No. 55,567

Term of patent 7 years

To all whom it may concern:

Be it known that I, Samuel J. Block, a citizen of the United States, residing at Connersville, in the county of Fayette and State of Indiana, have invented a new, original, and ornamental Design for a Cabinet, of which the following is a specification, reference being had to the accompanying drawing, forming a part thereof.

Figure 1 is a perspective view of a cabinet, a portion being illustrated in dotted lines, showing my new design.

Fig. 2 is a cross-sectional view taken on the line 2—2 of Fig. 1.

My new design is for a cabinet, the essential feature of which comprises a rounded corner provided with a raised flat panel having beveled portions on the sides thereof blending into the adjacent surfaces.

I claim:

The ornamental design for a cabinet, substantially as shown and described.

SAMUEL J. BLOCK,
